UNITED STATES PATENT OFFICE.

CHARLES D. HUFF, OF DALLAS, PENNSYLVANIA.

THILL-COUPING.

SPECIFICATION forming part of Letters Patent No. 433,347, dated July 29, 1890.

Application filed May 2, 1890. Serial No. 350,319. (No model.)

To all whom it may concern:

Be it known that I, CHARLES D. HUFF, of Dallas, in the county of Luzerne and State of Pennsylvania, have invented certain new and useful Improvements in Thill-Couplings; and I do hereby declare the following to be a full, clear, and exact description of the invention, such as will enable others skilled in the art to which it pertains to make and use it, reference being had to the accompanying drawings, which form part of this specification.

My invention relates to an improvement in thill-couplings; and it consists in the combination and construction of parts, which will be fully described hereinafter.

The object of my invention is to provide a thill-coupling in which the shafts are attached to the axle without the help of the usual coupling-bolts, and to make the shafts readily detachable at any time by simply raising them up at their outer ends, and thus do away with a necessity of having to remove some of the parts.

Figure 1 is a side elevation of a coupling embodying my invention. Fig. 2 is a plan view of the same.

A represents the clip, and B the socket to receive the head C upon the shaft-iron D, and which socket is secured to the under side of the axle by means of the recessed plate G, through which the bolts of the clips pass, and which plate forms a part of the coupling. The socket is shaped something like the letter **G**, and is made only about as wide as the shaft iron, and is provided with flanges H, to prevent the shaft-iron from having any lateral movement after its head has once been inserted into the socket. The lower outer end I of the socket, which extends forward any suitable distance and forms a support for the spring J, is provided with a notch in which the front end of the spring catches. This spring is made in the form of an elongated link, and is supported in position by having its front end catch in the notch in the end I and by having its rear end catch over the top of the plate G. The head upon the end of the shaft-iron may either be of the form here shown, or any other that may be preferred,

and has extending from opposite sides the two 50 studs or projections O, which bear against the upper side of the spring near its center for the purpose of exerting a downward pressure thereon. The springs, catching against the under side of the projections, serve to 55 force the upper end of the head up into the socket, and thus do away with any liability upon the part of the coupling to separate, and especially to prevent any rattling or noise while the vehicle is in motion. This spring, 60 by extending along upon opposite sides of the socket and the head, also serves to prevent any lateral play on the shaft-iron.

In order to remove the shafts from the vehicle, it is only necessary to raise the front 65 ends of the shafts, and then the lower shorter portion of the head rises out of the bottom of the socket, thus leaving the thill-iron free to be drawn out.

As will be seen, no bolts or other removable parts are used, and hence the shafts can be readily removed without the assistance of a wrench or other similar tool.

Having thus described my invention, I claim—

1. In a thill-coupling, the combination, with a socket having a projection at its rear side, and a shaft-iron having a head which fits in the socket, of a link separate from the socket and which passes around the socket, and having 80 its ends engage the said rear projection and the lower end of the socket, respectively, substantially as shown.

2. In a thill-coupling, the combination, with a socket having a projection on its rear side 85 and a notch in its lower end, and a shaft-iron having a head which fits in the socket, of a link which has its ends engage, respectively, the said rear projection and notched lower end, substantially as specified.

3. In a thill-coupling, the combination, with a socket having open sides, of a shaft-iron having laterally-extending projections, and a link which has its ends engage the rear side and lower end of the socket and the under 95 side of the said projections between its ends, substantially as described.

4. In a thill-coupling, the combination of

a socket and a shaft-iron having a head, of a link separate from the socket, and which has its inner end engage the rear side of the socket and its lower end the lower end of the socket, whereby it is supported and extends around the socket, substantially as shown and described.

In testimony whereof I affix my signature in presence of two witnesses.

CHARLES D. HUFF.
